SIGNAL TRANSMISSION CIRCUIT

E. Dudley Goodale, Bayside, N. Y., assignor to
Radio Corporation of America, a corporation of
Delaware

Application January 24, 1940, Serial No. 315,313

3 Claims. (Cl. 178—44)

My present invention relates to signal transmission circuits of the balanced line type, and more particularly to coupling networks employed in connection with balanced lines.

One of the main objects of my invention may be stated to reside in the provision of means for properly terminating a balanced signal transmission line, effectively suppressing longitudinal voltages and securing a limited amount of equalization.

Another important object of the invention is to provide a coupling network for a pair of balanced transmission lines, wherein the coupling network comprises a pair of tubes having output electrodes in push-pull relation, the lines being coupled into the cathodes of the tubes, and input electrodes of the tubes being additionally cross-connected to the lines thereby providing cancellation of push-push voltages.

Still another object of the invention is to provide a coupling network between a pair of balanced signal transmission lines and an unbalanced line, wherein the network comprises a pair of electron discharge devices arranged to deliver balanced voltages with minimum of push-push voltage, and a third electron discharge device has input electrodes coupled to the output of the pair of devices to provide an unbalanced voltage output.

Still other objects of my invention are to improve generally the simplicity and efficiency of coupling networks for balanced line systems, and more especially to provide such networks in an economical and reliable manner.

The novel features which I believe to be characteristic of my invention are set forth in particularity in the appended claims; the invention itself, however, as to both its organization and method of operation will best be understood by reference to the following description taken in connection with the drawing in which I have indicated diagrammatically several circuit organizations whereby my invention may be carried into effect.

In the drawing:

Fig. 1 shows one embodiment of the invention,
Fig. 2 illustrates a modification,

Fig. 3 shows another modification wherein balanced voltages are converted to an unbalanced voltage,

Fig. 4 shows a modification of the circuit of
Fig. 3.

Referring now to the accompanying drawing, wherein like reference characters in the various figures designate similar circuit elements, there

is shown in Fig. 1 a pair of electron discharge devices 1 and 2 which are included in the coupling network adapted to provide the coupling circuit between input and output balanced lines. 5 The lines 3 and 4 are shown as feeding voltage from a source of balanced voltage. The source 5 may produce alternating voltage in a frequency range of 60 cycles to about 8 megacycles. The source may be a signal source operating either 10 in the television video range or in the standard sound broadcast range. Regardless of the frequency of the signal voltage, or the frequency band width of the signal energy, the lead 3 is shown as having, merely by way of illustration, 15 a positive polarity relative to ground, while the lead 4 has a negative polarity. The term "balanced," therefore, indicates the voltage state when the two leads at any given instant are of opposite polarity relative to ground. The distribution line 3—4, for example, may be a twisted pair of leads adapted to transmit a wide band of television signal energy through an apartment house to one or more television receivers.

Regardless of the specific use of the circuits 25 shown, the coupling tube 1 has its cathode 6 connected to the cathode 7 of tube 2 through a pair of resistors R₁ and R₂ of equal magnitude; the junction of the resistors being grounded. The lead 3 is connected to the cathode end of resistor R₁, while lead 4 connects to the cathode end of resistor R₂. The signal grid 8 is additionally connected to lead 4 through condenser 10, while grid 9 is coupled to lead 3 through condenser 11. The plates of tubes 1 and 2 are connected to a point of properly chosen positive voltage through output load resistors R₃ and R₄. Coupling condensers 12 and 13 couple the tubes 1 and 2 respectively to output lines 3' and 4'. The grids 8 and 9 are returned to ground by grid leak resistors 15 and 16 respectively, the direct voltage developed across each of R₁ and R₂ biasing grids 1 and 2 respectively. If desired, a common bias resistor may be connected between the resistors R₁ and R₂ and ground.

45 Push-push and push-pull alternating voltages are applied to leads 3 and 4 from source 5; only the polarities of the push-pull voltages are shown. These voltages are applied directly to the cathode ends of resistors R₁ and R₂. The 50 parallel combination of R₁ and the reciprocal of tube 1 transconductance (G_{m1}) acts as the termination for the lead 3 side of the balanced lines, while the combination of R₂ and the reciprocal of tube 2 transconductance (G_{m2}) acts as the termination for the other side of the system.

The grid circuit of the tubes is a high impedance bridge circuit. Terming the impedance between cathode and ground of each tube as R_0 , it follows that:

$$R_0 = \frac{R_1}{1 + R_1 G_{m1}} = \frac{R_2}{1 + R_2 G_{m2}}$$

The applied signal voltages produce changes in the plate currents of the tubes, and thus in the signal voltages developed across the load resistors R_3 and R_4 . The signal input voltages are also cross-connected to grids 8 and 9. This has the effect of adding to the push-pull voltages produced across R_3 and R_4 . Push-push voltages are cancelled out in the grid circuits. The amount of cancellation can be made very large or small depending upon the degree of balance between the two sides of the system. It is desirable to make the amount of cancellation large. It will, therefore, be seen that the tubes 1 and 2 are connected in push-pull voltage reinforcing relation, while for push-push voltages they have the grid circuits in cancellation relation. Each of load resistors R_3 and R_4 are bypassed for high frequencies to ground by a condenser connected to an intermediate point. These condensers are designated as 1' and 2' respectively.

The modification in Fig. 2 differs from the arrangement of Fig. 1 only in that networks R_5 - 10 and R_6 - 11 are used to secure frequency discrimination. These networks should, of course, present a relatively high impedance in order not to upset the line termination. Otherwise their effect on the termination would have to be considered. Proper choice of the constants of R_5 - 10 and R_6 - 11 can produce more uniform response curves, where high frequency response is low.

It is possible to feed the balanced output voltages of tubes 1 and 2 to a device for converting the balanced voltages to an unbalanced voltage. For this purpose there may be employed a coupling device of the type disclosed in application Serial No. 279,686, filed June 17, 1939 by E. D. Goodale and R. A. Monfort, now Patent No. 2,256,084, issued Sept. 16, 1941. As shown in Fig. 3, the coupling device comprises a tube 20 having at least a cathode 21, a signal grid 22 and a plate 23. The signal grid 22 is connected to condenser 12, while cathode 21 is grounded through resistor R. The cathode end of resistor R is connected to condenser 13. The plate 23 is connected to a positive voltage point through a resistor R_7 , a part of which is bypassed to ground. The alternating voltage across resistor R_7 is "unbalanced" relative to ground, because the output lead 30 has a negative polarity to ground. The lead 30 may be connected to an amplifier, transmission cable (such as a co-axial line), or any other desirable utilization apparatus.

The signal grid 22 of coupling tube 20 is maintained at a negative bias by connecting the grid to ground through a grid leak resistor 31. In this type of circuit the opposite polarity signal voltage effects on the grid and cathode of tube 20 are additive in the plate circuit. A considerable increase in overall gain and improvement in ratio of push-pull to push-push voltages is effected over other known systems. Some frequency discrimination would be introduced by virtue of the cathode resistor R and the coupling condenser 13.

To avoid the last-named objection the circuit arrangement of Fig. 4 can be utilized. In this circuit arrangement the cathode of tube 20 is

established at the positive direct current potential of the plate of tube 2, and for this purpose the lead 32 connects the cathode end of resistor R to the plate end of load resistor R_4 . In order to obtain proper operating conditions it is, therefore, necessary to apply a positive direct current voltage to the signal grid of tube 20. This positive grid voltage should be sufficiently less than the cathode voltage to enable the signal grid to be at a negative potential with respect to the cathode. In other words, the resistor 34 in the case of Fig. 4, is connected to a point of positive potential. This means that the plate voltage supply of tube 20 would have to be greater than the plate voltage of tube 2. The circuit of Fig. 4 will give uniform amplification down to very low frequencies, and can be used up to several megacycles without any noticeable effect. In the circuits of both Figs. 3 and 4 longitudinal voltages existing in the balanced output leads of tubes 1 and 2 would be cancelled out in the input circuit of tube 20. This is a decided advantage in cases where longitudinal voltages still exist in the outputs of tubes 1 and 2. In other words, in the arrangements of Figs. 3 and 4 the undesirable push-push voltages would be minimized because the cancellation action of tubes 1 and 2 would be supplemented by the input circuit cancellation effect of tube 20.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In combination with a pair of electron discharge devices having input and output electrodes, an aperiodic wide band output circuit connecting the output electrodes in push-pull relationship, a pair of untuned high frequency wide band voltage transmission lines which are at opposite polarities with respect to a point of relatively fixed potential, means coupling each of said lines to one of the input electrodes of an associated one of said devices, additional means coupling each of said lines to the other of the input electrodes of each device in reversed relation with respect to said first coupling means, an impedance connected between said one input electrodes of said devices, means connecting substantially the midpoint of said impedance to said fixed potential point, an additional electron discharge device having at least a grid, cathode and anode, means impressing high frequency voltages of opposite polarity developed across said output circuit upon the grid and cathode respectively of said additional tube, and means for deriving from the anode circuit of said additional tube a voltage which is unbalanced with respect to said fixed potential point.

2. In combination with a pair of electron discharge devices having input and output electrodes, an aperiodic wide band output circuit connecting the output electrodes in push-pull relationship, a pair of untuned high frequency wide band voltage transmission lines which are at opposite polarities with respect to a point of relatively fixed potential, means coupling each of said lines to one of the input electrodes of an associated one of said devices, additional means coupling each of said lines to the other of the input electrodes of each device in reversed rela-

tion with respect to said first coupling means, an impedance connected between said one input electrodes of said devices, means connecting substantially the midpoint of said impedance to said fixed potential point, means for converting the balanced voltages appearing across said output circuit into an unbalanced voltage with respect to said fixed potential point, said last means comprising an electron discharge tube having at least a grid, cathode and anode, a resistive impedance in the space current path of said last tube, means impressing the balanced high frequency voltages of opposite polarity appearing across said output circuit upon the grid and cathode respectively of said last tube, and said last tube having said unbalanced voltage appears across said impedance.

3. In combination, an electron discharge tube provided with at least a control grid, a cathode and a plate, a resistor connected between the cathode and a point of relatively fixed potential and being disposed in the space current path of said tube, a second tube provided with at least a control grid, a cathode and a plate, a second

resistor connected between the cathode of the second tube and said fixed potential point and being disposed in the space current path of the second tube, a source of balanced high frequency voltage coupled to the cathode ends of said two resistors, a common high frequency voltage output circuit connected to the plates of both tubes in push-pull relation, and additional means coupling said high frequency voltage source to the control grids of said two tubes in a manner such that push-pull voltage components cancel out, a third electron discharge tube having at least a cathode, a control grid and an output electrode, a resistive impedance connected between the third tube cathode and a point of relatively fixed potential and being disposed in the space current path of the third tube, means for impressing the push-pull voltage components appearing across said output circuit between the grid and cathode of said third tube whereby there appears across an output circuit coupled to the third tube an output voltage which is unbalanced.

E. DUDLEY GOODALE.
